MEANS FOR STRIPPING LINKS IN A FIREARM

Burns Darsie, Watertown, Conn., assignor to the United States of America as represented by the Secretary of the Army

Application November 19, 1951, Serial No. 256,989

4 Claims. (Cl. 89—33)

This invention relates to automatic firearms having a high cyclic rate of fire and more particularly to an improved means for feeding ammunition thereto.

The nature of present day ammunition, the use of disintegrating metallic links for holding the rounds, the requisite of rapid feeding, firing, extraction and ejection with the limited operating energy available impose requirements for delinking the rounds from the link prior to chambering of such rounds to diminish the energy expended for said delinking.

One of the objects of the instant invention is to provide an improved means of delinking present day linked belt ammunition prior to entering the chamber without diminishing the cyclic rate of the firearm.

Another object of the invention is to provide an improved means of feeding linked ammunition to a rotatable feed wheel that supplies delinked rounds to a feedway prior to said round being chambered by a reciprocating member in a firearm.

A further object of the invention is to eliminate the necessity of having the reciprocating bolt member delink the round in the feedway thereby permitting an uninterrupted and smoother action of such member during the counter-recoil movement when the round is fed forwardly to its chambered position.

Still another object of this invention provides stripping means for delinking a linked round without undue strain on the links.

The invention accordingly provides a means of delinking a linked round from a linked belt of ammunition using a link similar to one that is shown and described in Patent 2,480,972, issued September 6, 1949, to R. S. Sanford et al.

These and further objects, which will become more apparent from the following disclosure, are obtained by the unique means illustrated in the accompanying drawing in which:

Fig. 1 is a schematic cross-sectional end view of the preferred embodiment of this invention; and

Fig. 2 is a schematic plan view of the feed wheel, one of the teeth of the sprockets being cut away to show the linked round and stripper.

Referring to the drawings, there is illustrated a portion of a receiver 12 having a feedway 14 in the upper part thereof. A spring-biased cartridge stop 16 is pivotally mounted on feedway 14 of receiver 12 to align a delinked cartridge 18 with the axis of a chamber in a barrel (not shown). Associated with the receiver 12 and conventionally mounted on the side thereof, a housing 20 is provided which primarily comprises a cartridge linked belt feeding trough 22, a link chute 24, and a feed wheel casing 25.

2

A sprocket or feed wheel 26 is rotatably mounted in casing 25 of housing 20 parallel to the longitudinal axis of receiver 12 on a shaft 28 for intermittent movement therewith. Feed wheel 26 comprises two spaced apart sprocket wheels positioned to engage the case of a cartridge. Shaft 28 is intermittently rotated by synchronistic means (not shown) through an arc equivalent to the pitch of the links, i. e., the lateral distance between the center line of adjacent linked cartridges 40. In the proximity of the feed wheel 26 a suspended support 30 is provided and is secured at 32 to wall 34 of casing 25. Support 30 is provided with a leg portion 36 that is positioned contiguous to an upper wall 38 of trough 22 thereby forming an independent upper portion cooperating with trough 22 to position the linked cartridge 40 prior to being fed into feed wheel 26. Support 30 terminates in a circular portion 42 on the free end thereof constructed to surround shaft 28 and having an outside periphery arranged to coincide with the root of sprocket teeth 68 of feed wheel 26. The periphery of portion 42 is also provided with a slightly eccentric cam lobe portion 74. Leg portion 36 is provided with an upwardly curved portion 76 disposed forwardly of and adjacent to cam lobe portion 74 for a purpose to be described.

25 Linked cartridge 40 is releasably held in a disintegrating metallic link 44 being of the conventional type similar to the link shown and described in the aforementioned Patent 2,480,972 that interlocks with adjacent links thereby forming a linked belt of ammunition. Link 44 is

30 constructed with a stripper bridge 46 thereby providing a space between a cartridge case when assembled thereto for a purpose to be described. On receiver 12 there is mounted a stripper 48 that coordinates with the feed wheel 26 and is approximately L-shaped in contour. One leg 50 is used to secure stripper 48 to the receiver 12 as shown at 52, and the other leg 54 protrudes into the housing 20 above the link chute 24. Leg 54 is provided with a blade-like end 56 that is constructed to pass through the space between the bridge 46 and the case of linked cartridge 40.

35 Housing 20 is provided with an inclined bottom wall 58 that connects trough 22 and chute 24 thereby forming a continuous passageway therebetween. The inclination of wall 58 is approximately parallel to an upper surface 60 of end 56 on stripper 48. A convexed ramp 62 complementary to curved portion 76 of leg 36 is secured to wall 58 immediately before and partially under an arcuate surface 64 on end 56 of stripper 48. Further down on the inclined wall 58 a link guide 66 is fastened thereon for a purpose to be described later.

40 Referring to Fig. 1 linked cartridges 40 are fed into trough 22 with the bridge 46 of link 44 downwardly disposed. As linked cartridge 40 is moved intermittently along trough 22 by feed wheel teeth 68 of feed wheel 26, bridge 46 of link 44 is cammed upwardly when passing over ramp 62 thereby forcing the cartridge against the curved portion 76 in leg 36 of support 30 thereby controlling the entrance of the stripper between the cartridge and stripper bridge 46. In the next phase of the feeding cycle the linked cartridge 40 is moved further along trough 22 thereby permitting the arcuate surface 64 to cam the link 44 downwardly partially away from the cartridge therein. The bridge 46 then continues along under leg 54 and over guide 66 to complete the delinking of the cartridge. The top contour of link guide 66 complementary to a concave surface 78 on the underside of stripper 48 maintains the bridge against the stripper 48.

during the final phase of delinking thereby prolonging the time of engagement of the link 44 with the cartridge. During these functions the cartridge is radially moved along an arcuate configuration 70 that is a continuation of surface 60 on leg 44 and is diametrically positioned from the rotatable center of feed wheel 26. While the cartridge is being delinked, it is releasably held against the configuration 70 by cam lobe 74 on circular portion 42 of support 30 to eliminate any tendency of the partially delinked cartridge from assuming an improper position in relation to the feed wheel 26 during the final operation of entirely removing the link 44 from the cartridge 18. Cam lobe 74 and configuration 70 also holds the cartridge partially linked until the following round has been engaged by teeth 68 of feed wheel 26. The transitory movements of the linked cartridge 40 over ramp 62 and guide 66 with the cooperation of curved portion 76 and cam lobe 74 prevents undue strain on link 44 when such link is being partially delinked from cartridge 18 and in conjunction with the contour of stripper 48 the paths of the link 44 and cartridge 18 are both controlled during stripping in such a manner that the clamping elements of the link are of a great assistance in maintaining control of the cartridges until stripping is nearly completed. Link 44 when free of cartridge 18 falls by gravity down chute 24. Cartridge 18 during successive movements of the feed wheel 26 is carried upwardly by such feed wheel until the cartridges are cammed into feedway 14 by a pivotally mounted spring biased lever mechanism 72 actuated by mechanism (not shown).

While there is shown a particular embodiment of this invention, it will be understood, of course, that I do not wish to be limited thereon, since many modifications may be made and therefore it is contemplated in the appended claims to cover any such modifications as fall within the true spirit and scope of this invention.

I claim:

1. In a firearm having a transverse feedway, a housing fixedly secured to the firearm adjacent the entrance of the feedway, and rotatable sprocket means mounted in the housing for advancing a belt of linked cartridges therethrough into the feedway, the combination of a feed trough extending into the housing to intersect the bottom portion of the rotative path of the sprocket means, a link chute extending upwardly into the housing to communicate with said feed trough, a stripper fixedly secured to the firearm and having an outwardly projecting blade-like portion extending into said feed trough beneath the sprocket means and into the path of the incoming linked cartridges, cam means in said feed trough for raising a linked cartridge into position to assure entry of said blade-like portion of said stripper between the link and the cartridge, said blade-like stripper portion having an arcuately formed underside for camming the link away from the cartridge during the continuation of the feeding movement thereof, a support fixedly secured at one end thereof in the housing to extend inwardly therein over said feed trough and partially encircle the sprocket means, an eccentric cam on said support for guiding a partially stripped cartridge along the upper surface of said blade-like stripper portion and thereby prolonging the interval of actual stripping operation, and cam means in said feed trough adjacent the communicating end of said link chute operative on the partially stripped link to maintain contact thereof with the cartridge associated therewith until the following successive cartridge is positively engaged by the rotating sprocket means.

2. In a firearm having a transverse feedway, a housing fixedly secured to the firearm adjacent the entrance to the feedway therein, said housing having a feed passage extending along the bottom thereof to terminate in a downwardly extending link chute, a feedwheel rotatably mounted in said housing and having a plurality of sprocket teeth depending into said feed passage for advancing a belt of linked cartridges therealong, a link stripper fixedly secured to the firearm above said link chute and having

a projecting bladelike portion extending outwardly along said feed passage into the path of the advancing cartridge belt for entry between each cartridge and the link associated therewith, and cam means in the top and bottom of said feed passage for successively forcing the cartridge and the link associated therewith toward each other during the respective stripping movements thereof to prolong the engagement therebetween until positive engagement of said sprocket teeth with the next following cartridge.

3. In a firearm having a transverse feedway, a housing fixedly secured to the firearm in alignment with the entrance to the feedway, said housing having a feed passage therethrough including a feed trough extending along the bottom thereof and a downwardly extending link chute communicating with said feed trough, a feedwheel rotatably mounted in said housing and having a plurality of sprocket teeth successively engageable with the cartridges in a linked belt for advancing the belt along said feed trough, a support member having one end thereof fixedly secured in said housing and extending above and parallel to said feed trough to terminate at the free end thereof in a feedwheel encircling portion, a link stripper fixedly secured to the firearm above said link chute and having an arcuate upper surface cooperating with said sprocket teeth to guide the cartridges upwardly toward the transverse feedway in the firearm, said link stripper having a projecting bladelike portion extending outwardly along said feed trough into the path of the advancing cartridge belt for entry between each cartridge and the link associated therewith, said bladelike portion having an arcuate lower surface for initiating the stripping of the cartridge from the link associated therewith, a cam lobe portion on the feedwheel encircling portion of said support member for camming the cartridge downwardly out of the rotative path imparted thereto by said sprocket teeth and into the link associated therewith to prolong the stripping engagement therebetween, and cam means in the bottom of said feed trough adjacent the entrance to said link chute for forcing the link upwardly toward the partially stripped cartridge to continue to prolong the stripping engagement therebetween until after positive engagement of said sprocket teeth with the next following cartridge thereby preventing any discontinuity in the feeding movement of the cartridge belt.

4. In a firearm having a transverse feedway, a housing fixedly secured to the firearm at the entrance to the feedway therein, said housing having an entrance for a belt of linked cartridges and a feed trough extending along the bottom thereof in communication with said entrance, a feedwheel rotatably mounted in said housing and having a plurality of sprocket teeth successively engageable with the cartridges for advancing the belt along said feed trough, a support member having one end thereof fixedly secured in said housing and extending above and parallel to said feed trough to terminate at the free end thereof in a feedwheel encircling portion, a link stripper fixedly secured to the firearm at the end of said feed trough and having an arcuate upper surface cooperating with said sprocket teeth to guide the cartridges upwardly toward the transverse feedway in the firearm, said link stripper having a projecting bladelike portion extending outwardly along said feed trough into the path of the advancing cartridge belt, a convex cam disposed in the bottom of said feed trough adjacent the projecting end of said link stripper for lifting each linked cartridge into position to assure entry of said link stripper end between the cartridge and the link associated therewith, said support member having a concave portion therein in coaxial alignment with said convex cam to permit the lifting of the linked cartridge, said bladelike stripper portion having a convex underside surface adjacent the free end thereof for forcing the cartridge link out of engagement with the cartridge associated therewith, a cam lobe portion on the feedwheel encircling portion of said support member projecting beyond the root periphery of the

sprocket teeth for camming the cartridge downwardly out of the rotative path imparted thereto by said feedwheel and into the link associated therewith, and an arcuate cam surface in the bottom of said feed trough adjacent the exit thereof for forcing the link upwardly out of the stripping path thereof, said cam lobe portion and said arcuate cam surface being disposed in adjacent relation to prolong the stripping engagement between the link and the cartridge until said sprocket teeth effect positive engagement of the next following cartridge to prevent 10

discontinuity in the feeding movement of the cartridge belt.
